CLAIM

The ornamental design for a display panel with a computer icon, as shown and described.

DESCRIPTION

FIG. 1 is a front view of a display panel with a computer icon in accordance with the new design; and,

FIG. 2 is a front view of a second embodiment thereof.

The broken lines in both views are for illustrative purposes and do not form part of the claimed design.

The perimeters of the underlying display panel and the computer icon are understood to be flush.
